UNITED STATES PATENT OFFICE.

PAUL F. CALDWELL, OF LOS ANGELES, CALIFORNIA

PORTABLE RABBIT-HUTCH.

1,159,744.

Specification of Letters Patent.

Patented Nov. 9, 1915.

Application filed May 20, 1914. Serial No. 839,787.

To all whom it may concern:

Be it known that I, PAUL F. CALDWELL, a citizen of the United States, residing at Los Angeles, in the county of Los Angeles and State of California, have invented a new and useful Portable Rabbit-Hutch, of which the following is a specification.

My object is to make portable rabbit hutches with perforated elevated floors, thoroughly 19 ventilated without drafts, and having convenient feed mangers; and my invention consists of the novel features herein shown, described and claimed.

Figure 1 is a side elevation of rabbit 15 hutches embodying the principles of my invention. Fig. 2 is an end elevation. Fig. 3 is a cross section. Fig. 4 is a fragmentary plan section. Fig. 5 is a fragmentary perspective of one of the feed mangers.

20 Rabbit hutches embodying the principles of my invention contain a plurality of independent compartments. In Fig. 1 I have shown compartments 1, 2, 3 and 4 on one side, and in Fig. 3 I have shown a partition 5, there being a second row of compartments 6 on the opposite side of the partition 5 from the row 1, 2, 3 and 4. A row of posts 7 extends downwardly from one side of the frame and a second row of posts 8 extends 25 downwardly from the other side so as to hold the compartments elevated some distance from the ground 9.

End walls 10 and 11 extend upwardly from the floor line and extend equal distances each way from the partition 5. Side sills 12 and 13 are secured to the posts 7 and 8 at the floor line and said side sills are connected by cross sills 14. The perforated floor is made up by securing slats 16 to the 30 lower faces of the cross sills 14. Rafters 17 are secured to the extreme upper ends of the posts 7 and 8. The end walls 10 and 11 are secured to the end ones of the cross sills 14 and to the rafters 17. The ridge pole 18 extends upwardly from the partition 5. The upper side sills 19 and 20 are secured to the ends of the rafters 17. The roof 21 is mounted upon the ridge pole 18 and upper side sills 20. The gable ends are closed by 35 50 sections of screen 22.

Intermediate studs 23 and 24 extend upwardly from the side sills 12 and 13 intermediate of the posts 7 and 8 and screen walls 25 and 26 are inserted between these 45 55 studs and the partition 5 and similar screen walls are inserted between the central pair

of the posts 7 and 8 so that the space above the floor is divided into two rows of compartments opening outwardly.

A screen door 27 is connected to the side 60 sill 12 by hinges 28 so as to close simultaneously all of the compartments on that side and a similar screen door 29 is connected to the side sill 13 by hinges 30 so as to close simultaneously all of the compartments on 65 the other side. The doors swing upwardly below the upper side sills 19 and 20 and are held closed by buttons 31.

A post 32 is inserted in the opening of the apartment 2 and extends from the lower 70 end of the stud 23 upwardly and outwardly from the stud and a section of screen 33 is secured to this inclined post and to the screen partition at the bottom and extends backwardly part way to the partition 5 and 75 then laterally to the screen partition so as to form a manger 34 open at the front.

A bar 35 is inserted in the screen door frame 27 so as to fit against the bar 32 when the door is closed and the space 36 between 80 the bar 35 and the stud or cross bar 37 of the screen door is left open. In this way I provide a manger which is always open from the outside so that feed may be placed in the manger for the rabbits and drawn by 85 the rabbits through the screen, one manger serving for two compartments. In a similar manner a manger 38 is constructed for the remaining two apartments of that side and two more mangers are constructed for 90 the other side. A center sill 39 is inserted below the cross sills 14 substantially parallel with the lower side sills 12 and 13 and the lower edge of the partition 5 is secured to this center sill. 95

In this manner I construct rabbit hutches which are readily portable when in use, that is, they may be moved step by step over any given area of yard as desired and the hutches are thoroughly ventilated 100 without being open to drafts and are conveniently arranged for caring for and feeding the animals and for removing the animals.

The details of construction may be varied 105 in many ways without departing from the spirit of my invention as set up in the following claims.

I claim:—

1. In a rabbit hutch, a partition formed 110 of coarse screen, a second section of screen mounted to coact with the first screen so as

to form a manger closed all the way around except at the front so that feed may be inserted through the open front and so that the animals may eat feed through the 5 screens.

2. In a rabbit hutch, an inclosure open at the front, a partition extending backwardly from the opening in the front and formed of coarse screen, a second section of coarse 10 screen mounted to co-act with the partition, so as to form a manger closed all the way around except at the front, so that feed may

be inserted through the open front and so that the animals may eat the feed through the screen from both sides, and screen doors 15 hinged at their bottoms and swinging upwardly to close the compartments on each side of the partition without closing the manger.

PAUL F. CALDWELL.
